CONCERTINA GRILL

Olof Holger Berglund, Alvdalen, Sweden, assignor to Aktiebolaget Abbin Hagstrom, Alvdalen, Sweden, a joint stock company

Filed Oct. 18, 1961, Ser. No. 67,131

Term of patent 7 years

(Cl. D56—1)

The FIGURE is a perspective view of a concertina grill embodying my new design.

The broken line showing of an accordion in the FIGURE is for illustrative purposes only.

I claim:

The ornamental design for concertina grill, substantially as shown and described.
